SOAP CAKE HOLDER

Gustav J. Sickelka, Philadelphia, Pa.

Application August 29, 1951, Serial No. 244,241

3 Claims. (Cl. 45—28)

1

My invention relates to a shaving soap holder of the type adapted to be attached to a conventional bath room fixture or to a wall of the bathroom.

The object of the invention, which is set forth in the following specification and which is shown in the accompanying drawings, is to produce an improved attachment of the type set forth.

In the drawings:

Fig. 1 is a perspective view of a shaving soap holder embodying the invention.

Fig. 2 is a sectional view looking in the direction of line 2—2 on Fig. 1.

The holder illustrated includes a bracket formed of ears 10 and 12 located in parallel planes and intermediate portions 14 and 16 which are located in the same plane but are normal to each other. The ear 12 is provided with a hole 18 for the passage of a screw or other such means whereby the holder may be secured to a bath room fixture, such as the stem of a conventional soap dish, not shown, or to any other fixed member such as the wall of the bathroom. The ear 10 has rigidly secured to it, as at 20, a disc 22 through the hub 24 of which is passed a spindle 26 to the outer of which is secured a handle 28. To the inner end of spindle 26 is rigidly secured, by means of a screw 30, a disc 32 whereby, the turning of handle 28 will rotate disc 32. The disc 32 is provided with a plurality of prongs 34 on which a cake of soap 36 is adapted to be impaled as shown in Fig. 2. By this arrangement the shaving brush 38, after being moistened, is held against the cake of soap while the latter is rotated by turning handle 26.

In order to prevent splashing and in order to provide means for retaining such lather as may not be carried off by the brush, I provide a guard member formed of a cylindrical body 40 through which the brush is inserted, and a conical or flaring rim 42 which is adapted to encircle the outer edge 44 of the soap cake as best shown in Fig. 2. By this arrangement, splashing which results from rapid rotation of the soap cake against the brush is confined by the guard and excess lather 46 which is not initially carried off by the brush will be available when resoaping of the particularly tough portions of the beard is needed.

In order to permit adjustment of the guard as the soap cake wears down, the portion 14 of the bracket is provided with a slot 48 which is parallel to the axis of rotation of the soap

2

cake, and the guard is mounted on an arm 50 which passes through slot 48 and which is secured in the desired position by turning a wing nut 52 which threadedly engages the outer end 5 of the arm 50. By this arrangement, when the soap cake wears down somewhat, the wing nut 52 is loosened, and the guard is moved, to the right as shown in Fig. 2, until the flared end 42 of the guard again engages the outer edge of the soap cake.

In order to be able to move the guard into the out of the way position shown in broken lines in Fig. 1, the portion 16 of the bracket is provided with a slot 54 which leads from, and is normal to slot 48. By this construction, the wing nut 52 is loosened, and the arm 50 is moved, in slots 48 and 54 to the position shown in broken lines in Fig. 1 in which the guard is spaced from the soap cake and from the disc 32 which supports the soap cake. The guard is moved to the broken line position of Fig. 1 either when it is not desired to use it or while a fresh cake of soap is being mounted on disc 32.

What I claim is:

- 25 1. A soap cake holder including a bracket adapted to be secured to a support, a disc rotatably mounted on said bracket, means for securing a soap cake to said disc with a side of said cake abutting said disc, means for rotating said disc 30 and said soap cake, an annular, open-ended guard adapted to engage the opposite side of said soap cake, and means mounting said guard on said bracket for movement into, and out of, engagement with said soap cake.
- 35 2. The structure recited in claim 1 in which the last mentioned means includes a slot formed in said bracket, and an arm carrying said guard and movable in said slot.
- 40 3. The structure recited in claim 2 in which a portion of said slot is disposed substantially parallel to the axis of rotation of said disc, and another portion of said slot is disposed at an angle to said axis..

GUSTAV J. SICKELKA.
